DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY.

KNEE CONTROL MECHANISM FOR ELECTRIC-SEWING-MACHINE CABINETS.

Application filed June 9, 1928. Serial No. 284,181.

This invention relates to electric sewing machines of the cabinet type and has for an object to provide a simple and inexpensive form of knee-control mechanism adapting a 5 sewing machine motor-controller of the standard straight-pull or draw-bar operated type for installation in a sewing machine cabinet or table.

To this end the controller-unit is mounted 10 adjacent the end wall of the cabinet or table in an inclined position; the free end of the draw-bar of the controller-unit being inclined upwardly and toward the front of the table from the controller-body. At its 15 free end the controller operating draw-bar is connected to one arm of a bellcrank-lever operating in a plane normal to the plane of the base-plate of the controller-unit. The other arm of the bellcrank-lever extends in 20 the same general direction as the draw-bar and is connected to the upper end of a knee-shift lever which is mounted in an oppositely inclined position, whereby the lower end of the knee-shift lever is carried forwardly and 25 disposed below the lower edge of the front wall or panel of the sewing machine cabinet, in a position for convenient knee-operation. The controller-unit, bellcrank-lever and knee-shift lever are preferably mounted 30 on a supporting plate which is secured to the end-wall of the sewing machine table. The knee-shift lever preferably includes a curved extensible portion which is adjustable to 35 suit the operator.

In the accompanying drawings, Fig. 1 is 40 a front elevation of an electric sewing machine cabinet outfit embodying the invention. Fig. 2 is an inner face view of the end-wall of the cabinet showing the motor-controller operating mechanism. Fig. 3 is an elevation looking in the direction of the arrows 3, 3, Fig. 2. Fig. 4 is an elevation looking in the direction of the arrows 4, 4, Fig. 2, and Fig. 5 is a disassembled perspective view of the extensible arm of the knee-shift lever.

The invention is shown as embodied in a drop-head sewing machine cabinet or table having a top 1, end walls 2, 3, front wall or panel 4 and rear wall 5 defining the usual 50 cavity into which the sewing machine head 6 and its driving motor 7 are lowered when not in use.

Secured to the inner side of the end wall 3 is a supporting base 8 to which is secured

by screws 9 a standard straight-pull or draw-bar operated sewing machine motor-controller of the carbon-compression type, such as disclosed in my copending applications Serial No. 240,587, filed Dec. 16, 1927, and Serial Nos. 284,180 and 284,182, filed herewith. 55 Such a controller-unit comprises a base-plate 10 to which is fastened by screws 11 a carbon compression type rheostat 12 including a pull-rod 13 on which is screwed a head 14 embraced by the ends of the arms 15 which extend inwardly from the side members 16 at the ends of the cross-head 17 connected to the draw-bar or straight-pull operating member 18 which passes through an aperture 19 in the wall 20 bent upwardly from 60 the base-plate 10. Recovery springs 21 serve to restore the draw-bar to initial or "off" position when the pull thereon is relieved.

The controller-unit is mounted in an inclined position, Fig. 2, adjacent the end wall 75 3 of the table, so that the free end of the draw-bar 18 extends upwardly and forwardly or toward the operator from the controller-body 12. Spot-welded to the plate 8 is the foot 22 of a bracket 23 on which is fulcrumed at 24 a bellcrank-lever the arm 25 of which is slotted at 26 to operatively engage the stud-screw 27 secured to the draw-bar 18. The other arm 28 of the bellcrank-lever projects through the aperture 29 in the knee-shift lever 30 to be 80 85 described. The bellcrank-lever 25, 28 is disposed to operate in a plane transverse to the plane of the plate 8 and end-wall 3.

The knee-shift lever 30, Fig. 2, is inclined oppositely to the controller-unit and is fulcrumed at 31 on the bracket 32 which is spot-welded to the plate 8. The plane of operation of the knee-shift lever 30 is transverse to the plane of operation of the bellcrank-lever 25, 28 and is also transverse to the plane of the 90 base-plate 8.

The knee-shift lever 30 includes a section 33 which is swingable about the pivot-screw 34 to the concealed or non-operating position, shown in dotted lines in Fig. 2. The section 100 33 of the knee-shift lever includes the curved extensible knee-engaged portion 35 which is formed with a slot 36 to receive the guide-tongue 37 bent upwardly from the end of the member 33. The member 33 is formed at its lower curved end with a slot 38 through which passes the shank of the thumb-screw 39 threaded into the member 35. The curved

extensible portion 35 of the knee-lever is adjustable, as shown in Fig. 1, to suit the operator.

By referring to Fig. 2 it will be seen that when the swingable section 33 of the knee-shift lever is in its operative or full-line position, the lever as a whole lies substantially in a plane, so that the point of application of the knee-pressure is in the plane of operation of the straight portion 30 of the lever. This avoids any cramping action upon the fulcrum support 32 and also avoids any tendency for the knee-pressure to swing the section 33 about the screw 34.

The rheostat 12 is connected in series with the motor 7 to the usual current supply outlet by suitable wiring.

It will be understood that by arranging the controller-unit and knee-shift lever at opposite inclinations adjacent the end wall of the sewing machine table, a standard straight-pull controller unit, common to various types of electric sewing machine outfits, is adapted for knee-shift operation in a cabinet outfit; the operating mechanism being of the simplest character with a bellcrank-lever as the only intermediate element in the train of connections between the knee-shift lever and the draw-bar of the standard controller unit.

Having thus set forth the nature of the invention, what I claim herein is:

1. The combination with a sewing machine table having an end wall, of a draw-bar operated sewing machine motor-controller unit mounted adjacent the inner side of said end wall in an inclined position with the free end of the draw-bar extending upwardly and forwardly or toward the operator from the controller-body, a bellcrank-lever disposed to operate in a plane transverse to the plane of the

end-wall of the table and having one of its arms connected to the draw-bar of the controller, and a knee-shift lever inclined oppositely to the controller-unit and connected at its upper end to the other arm of said bellcrank-lever. 45

2. The combination with a supporting plate, of a draw-bar operated sewing machine motor-controller unit mounted on said plate so that the direction of pull of the draw-bar is substantially parallel to the latter, a bellcrank-lever fulcrumed on said plate to operate in a plane transverse to the latter, one arm of said bellcrank-lever being connected to said draw-bar, and a knee-shift lever fulcrumed on said plate and connected to the other arm of said bellcrank-lever, the plane of operation of the knee-shift lever being transverse to said plate and to the plane of operation of said bellcrank-lever. 55 60

3. The combination with a sewing machine table having an end-wall, of a sewing machine motor-controller unit mounted adjacent said end wall, and a knee-shift lever connected to operate said controller-unit and having a curved extensible knee-engaged portion. 65

4. The combination with a sewing machine table having an end-wall, of a sewing machine motor-controller unit mounted adjacent said end wall, and a knee-shift lever fulcrumed adjacent said end wall and connected at one end to operate said motor-controller unit, the other end of said knee-shift lever extending inwardly and downwardly from said end wall and including an inwardly extensible knee-engaged portion. 70 75

In testimony whereof, I have signed my name to this specification.

DANIEL H. CHASON.
